JESSE ALEXANDER, OF BROOKLYN, NEW YORK, ASSIGNOR OF ONE-HALF
TO BERNARD CRONSON, REUBEN CRONSON, AND SOLOMON H. SIEGEL,
OF NEW YORK, N. Y.

TYPE-WRITER CARRIAGE CONSTRUCTION.

SPECIFICATION forming part of Letters Patent No. 761,639, dated June 7, 1904.

Application filed December 29, 1902. Renewed December 17, 1903. Serial No. 185,593. (No model.)

To all whom it may concern:

Be it known that I, JESSE ALEXANDER, a citizen of the United States, residing at Brooklyn, Kings county, New York, have invented 5 certain new and useful Improvements in Type-Writer Carriage Construction, of which the following is a full, clear, and exact description.

My invention relates to improvements in type-writers, and particularly to the carriage 10 construction thereof.

The object of my invention is to improve the construction of that part of a type-writer which is designed to carry the platen and form it in such a manner that while it is rigid 15 and reliable it may be readily removed from the other parts of the machine for the purpose of repair or adjustment. It is desirable in many kinds of type-writer construction that the type-writer may be able to do work 20 on different sizes of papers, sometimes of width greater than the capacity of the ordinary carriage. For this purpose it is necessary either to have another machine which will take the required width of the paper or 25 to remove the ordinary carriage and platen and substitute one of the proper width or capacity. In doing this it is of course advisable that as little mechanical ingenuity as possible be required of the operator and that 30 the mechanism be not disarranged.

The invention consists in mounting the carriage in such manner that the entire structure may be quickly and readily removed from the main body of the machine. While attached 35 thereto it has the greatest rigidity possible.

Figure 1 is a plan view of those parts of a type-writer embodying the improvements of my invention. Fig. 2 is a front elevation of the same, part being broken away. Fig. 3 is 40 an end elevation of the same, part being broken away. Fig. 4 is a cross-section and elevation of the improved construction by means of which the carriage is secured to the machine.

1 is a fragment of the main body of the 45 machine. 2 is a supporting-plate carried thereby and extending across from side to side of the machine. In this supporting-plate

is pivoted the escapement-shaft and pinion³ for engaging rack 4.

5 is the connecting-plate, which carries the main guide-rod 6 for the carriage. The connecting-plate has at the two ends the brackets 7 7, which secure the main guide-rod 6. The brackets may be secured to the connecting-plate 5 by means of screws 8. (Shown dotted 55 in Figs. 2 and 3.) The central portion of the connecting-plate is recessed or cut away to make allowance for the escapement mechanism.

On the guide-rod 6 slides the sleeve 9, which 60 is secured to the bar 10. This bar 10 connects the side frames 11 and 12 of the carriage structure. To these side frames are pivoted the side plates 13 and 14, which provide bearings for the platen-shaft. (See Fig. 3.) The weight of the 65 carriage and attached parts is borne at the rear by the guide-rod 6 and at the front by the track 16, which is secured to the frames of the machine.

17 and 18 are guide-rollers carried by the 70 bar 19, which connects the two side frames 11 and 12.

20 is an auxiliary guide-rail by means of which the platen is shifted through the medium of the roller 21, carried by the rod 22, 75 which is mounted in the side plates 13 and 14.

The rack 4, which engages with the escapement-wheel 3, is connected, by means of the arms 23 and 24, to the shaft 25, pivoted in the side frames 11 and 12. 26 is a handle by 80 means of which this shaft 25 may be rotated, so as to withdraw the rack 4 from engagement with the escapement-wheel 3. Since the other parts of the escapement are not concerned with this invention, it is unnecessary 85 to describe them here.

The construction by means of which the connecting-plate 5 is secured to the supporting-plate 2 of the machine is shown in detail in Fig. 4. 26' is a bushing carried by the supporting-plate 2, which projects upward and fits into a recess in the connecting-plate 5, but does not quite extend through the same. The interior of this bushing is threaded and may 90

be engaged by the fastening-screw 27. When this screw is worked down into the bushing and clamped tightly, the connecting-plate 5 is secured to the supporting-plate 2, and when 5 the screw 27 is withdrawn the parts attached to the connecting-plate—*i.e.*, the entire carriage construction—may be lifted bodily and withdrawn from the machine. At this time it will be noted that the guide-wheels 17 and 10 18 are perfectly free to pass to the rear of the track 16 and that the rack 4 will be freed from the escapement-wheel 3 by simply lifting the parts. 28 is a strip, preferably of metal, secured to the connecting-plate 5 by means of 15 the screw 29. This strip is slotted near the end opposite to that which is attached to the connecting-plate, so that the screw 27 may be passed partially through it. The screw is, however, provided with a shoulder 30, which is 20 of sufficient size to provide a bearing. When the screw has been thrust partially through the strip 28, it may then be partially drawn out to the end of the slot to the contracted portion, where it will be gripped about the annular 25 recess which is formed in the screw immediately below the shoulder 30. It will be noted in Fig. 1 that the slotted portion in the strip 28 is contracted at 31, so as to afford a slight resistance to the annular recessed portion of 30 the screw as it is being drawn into place. This insures that the screw will be held securely and will not be lost out when it has been removed from the bushing 26'. This bushing I prefer to form separate from the 35 connecting-plate 2, both because this is an economical method of manufacture and because it affords a means for adjustment of the same. 32 is a check-nut which may be provided to more effectively hold the bushing in 40 its place in the supporting-plate 2. When the strip 28 is used, it will be perceived that on turning the screw down tightly the strip forms a seat for the shoulder 30 of the screw 27 and affords a springy contact against the 45 top of the connecting-plate 5. To remove the carriage, it is merely necessary to loosen the screws 27 at the two opposite sides of the machine and then lift the carriage construction entirely free. For convenience of access I 50 locate the fastening-screws near the outer ends of the connecting-plate, so that the carriage need be moved but a short distance to one side in order to reach them easily. If it should be desirable or necessary to further separate 55 the sleeve 9 and attached parts from the guide-rail 6, this may be done by simply removing the screws 8 which fasten the bracket 7 to the connecting-plate 5, one or both of the brackets 7 being recessed on the inside to secure the 60 corresponding end of the rod 6.

The advantages of the simple construction set forth and described herein will be apparent to any one skilled in the art of type-writer construction, as well as to the operator.

What I claim is—

65

1. In a type-writer the combination with the main back supporting-plate of a continuous connecting-plate resting upon and supported by said main back plate, side brackets attached to said connecting-plate, a rear guide-rail carried by said brackets, and a carriage construction adapted to slide longitudinally of said rail, a fastening-screw at each end of said connecting-plate having a head accessible from above, said screw passing downwardly through 75 the back plate for holding said connecting-plate against said main back plate.

70

2. In a type-writer the combination with the main back supporting-plate of a continuous connecting-plate resting upon and supported by said main back plate, side brackets attached to said connecting-plate, a rear guide-rail 80 removably carried by said brackets, and a carriage construction adapted to slide longitudinally of said rail, a bushing carried by the 85 said supporting-plate adjustable therein and extending upward into a recess in said connecting-plate and a screw working downward in said bushing for securing said plates together.

90

3. In a type-writer the combination with the main back supporting-plate of a continuous connecting-plate resting upon and supported by said main back plate, side brackets attached to said connecting-plate, a rear guide-rail carried by said brackets, and a carriage construction adapted to slide longitudinally of said rail, a bushing carried by the 95 said supporting-plate extending upward into a recess in said connecting-plate for securing said plates together, 100 and a fastening-screw passing downward into said bushing for securing the said plates together.

95

4. In a type-writer the carriage construction including a main back supporting-plate, a connecting-plate resting thereon, fastening-screws near each end passing downward through said connecting-plate, holding-strips attached to said connecting-plate said fastening-screws passing through 105 said holding-strips.

100

5. In a type-writer the carriage construction including a main back supporting-plate, a connecting-plate resting thereon, fastening-screws near each end passing downward 115 through said connecting-plate, springy metallic holding-strips attached to said connecting-plate said fastening-screws passing through said holding-strips.

110

6. In a type-writer the carriage construction including a main back supporting-plate, a connecting-plate resting thereon, fastening-screws near each end passing downward through said connecting-plate, springy metallic holding-strips attached to said connecting-plate said fastening-screws passing through 120 slotted openings in said holding-strips.

115

7. In a type-writer a carriage construction

including a supporting-body, a continuous connecting-plate extending across from side to side, a bushing extending upward through a recess in said connecting-plate, a fastening-screw taking into said bushing and a holding-strip attached to said connecting-plate for said screw said screw being adapted to clamp the connecting-plate against the supporting-body.

8. A type-writer carriage construction including a supporting-body, a continuous connecting-plate mounted thereon and extending from side to side thereof, brackets carried at either end of the connecting-plate, a guide-rail in front thereof, platen-carrying frames adapted to slide longitudinally of said rails, a rod connecting said platen-frames, guide-rollers carried by said rod their axes extending forwardly above and below the said stationary rail.

20 9. A type-writer carriage construction including a supporting-body, a continuous connecting-plate mounted thereon and extending from side to side thereof, brackets carried at either end of the connecting-plate, a guide-rail in front thereof, platen-carrying frames adapted to slide longitudinally of said rails, a rod connecting said platen-frames, guide-rollers carried by said rod their axes extending forwardly above and below the said stationary rail, and escapement mechanism including a ratchet projecting upward through a cut-out portion of said connecting-plate, a pivoted rack carried by the said platen-carrying frames for engagement with said ratchet.

35 10. A type-writer carriage construction including a supporting-body, a continuous connecting-plate mounted thereon and extending from side to side thereof, fastening-screws passing downward through said connecting-plate, brackets carried at either end of the connecting-plate, a guide-rail in front thereof, platen-carrying frames adapted to slide lon-

gitudinally of said rails, a rod connecting said platen-frames, guide-rollers carried by said rod their axes extending forwardly above and below the said stationary rail.

11. A type-writer carriage construction including a supporting-body, a continuous connecting-plate mounted thereon and extending from side to side thereof, fastening-screws 50 passing downward through said connecting-plate, bushings carried by said supporting-body extending upward into recesses in said connecting-plate, brackets carried at either end of the connecting-plate, a guide-rail in front thereof, platen-carrying frames adapted to slide longitudinally of said rails, a rod connecting said platen-frames, guide-rollers carried by said rod their axes extending forwardly above and below the said stationary 60 rail.

12. A type-writer carriage construction including a supporting-body, a continuous connecting-plate mounted thereon and extending from side to side thereof, fastening-screws 65 passing downward through said connecting-plate, bushings carried by said supporting-body extending upward into recesses in said connecting-plate, brackets carried at either end of the connecting-plate, a guide-rail in 70 front thereof, platen-carrying frames adapted to slide longitudinally of said rails, a rod connecting said platen-frames, guide-rollers carried by said rod their axes extending forwardly above and below the said stationary 75 rail, and escapement mechanism including a ratchet projecting upward through a cut-out portion of said connecting-plate, a pivoted rack carried by the said platen-carrying frames for engagement with said ratchet.
